VIRGINIA WESTERVELT SMITH, OF WILLIAMSPORT, PENNSYLVANIA.

NON-REFILLABLE BOTTLE.

1,096,135.

Specification of Letters Patent. Patented May 12, 1914.

Application filed September 30, 1913. Serial No. 792,638.

To all whom it may concern:

Be it known that I, VIRGINIA W. SMITH, a citizen of the United States, residing at Williamsport, in the county of Lycoming and State of Pennsylvania, have invented a new and useful Non-Refillable Bottle, of which the following is a specification.

The present invention appertains to non-refillable bottles, and aims to provide a novel and improved device of that character.

It is the object of this invention to provide a simple and efficient means coöperable with a bottle neck, to permit the contents of the bottle to be discharged and to prevent the re-filling of the bottle, after the original contents has been poured thereinto.

Another object of the present invention is to provide a device of the nature indicated, including a stopper, which is detached from the device prior to the filling of the bottle, and in order that the bottle may be readily filled, the stopper being insertible into the device, to close the filling means.

Another object of the present invention is to provide a baffle coöperating with the bottle neck to control the discharge of the contents of the bottle, and carrying the stopper, the bottle neck having a restricted opening into which the stopper is insertible when the baffle is slid inwardly or toward the body of the bottle.

With the foregoing general objects outlined and with other objects in view, which will be apparent as the nature of the invention is better understood, the present invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein:

Figure 1 is a fragmental view of a bottle embodying the present improvements, parts being broken away and parts being shown in section. Fig. 2 is a transverse section taken on the line 2—2 of Fig. 1. Fig. 3 is a view similar to Fig. 1, illustrating the bottle partially inverted, in which condition the contents are adapted to be discharged or decanted.

The present invention is applicable to any

bottle or container 1 having a suitable neck 2. In carrying out the present invention, the neck 2 is provided with an outturned rim or flange 3 at its mouth, and is provided with an internal collar 4 below the mouth, which provides a restricted opening 5. A gasket or washer 6 of rubber, cork, or any other suitable material embraces the neck 2 and seats upwardly against the rim or lip 3. The baffle 7 is in the form of an annular inverted channel which is disposed loosely over the rim of the bottle neck. This baffle includes the imperforate tubular portion 8, which is disposed concentrically within the bottle neck, and the outer end of which terminates in an imperforate annular apron 9 depending loosely over the rim of the bottle neck and over the sides of the said neck. The baffle may be constructed of glass, or any other suitable material, the edge of the apron 9 being provided with the inwardly projecting lugs 10 which may be formed in any convenient manner. The lugs 10 project toward the bottle neck and are disposed below the rim or lip 3, the lugs 10 being adapted to engage or contact with the gasket or washer 6 when the baffle is drawn outwardly or upwardly. When the baffle is seated upon the rim of the bottle neck, the lugs 10 will be spaced below the gasket or washer 6, as seen in Fig. 1, while when the baffle is moved outwardly, as seen in Fig. 3, the lugs 10 will engage the washer 6, to limit the outward movement of the baffle. The baffle is thus permitted to have a limited longitudinal or axial movement with respect to the bottle neck, the gasket or washer 6 preventing the lugs 10 and the rim or lip 3 of the bottle neck from being broken or injured, as will be apparent. The tubular portion 8 is provided at its inner or lower end with an inner annular groove or channel 11 for the purpose which will presently appear.

The stopper 12, which may be constructed of cork, rubber, or other suitable material, is insertible into and through the tubular portion 8 of the baffle, and has an enlarged head 13 to fit snugly within the tubular portion 8. The body of the stopper is relatively smaller in diameter than the tubular portion 8, so as to fit within the restricted opening 5, the opening 5 being smaller in diameter than the tubular portion 8. A leaf spring 14 is secured diametrically through the body of the stopper

12, and has its terminals bent into curved resilient catches 15. The catches 15 are adapted to be compressed or flexed toward each other, when the stopper is inserted into the baffle, in order that when the cork is pushed inwardly or downwardly, as seen in Fig. 1, the catches 15 will snap outwardly into the groove 11, so as to lock the cork in position. Thus, the cork is locked against removal or displacement, the head 15 of the cork or stopper fitting tightly within the tubular portion 8 of the baffle to close the passage through the baffle. The cork or stopper 12 is of sufficient length, to fit tightly within the opening 5 when the baffle is moved inwardly or downwardly, as seen in Fig. 1, the inner end of the stopper 12 engaging within the opening 5 when the baffle is seated against the bottle neck and being withdrawn from the said opening when the baffle is slid outwardly, as seen in Fig. 3.

In use, the bottle when sold or furnished to the user, is equipped with the baffle and the stopper is removed from the baffle. In this condition, the baffle is open, and the bottle may be readily filled by pouring the liquid through the tubular portion 8, from whence it will flow through the opening 5 into the body of the bottle. After the bottle has been filled the stopper is inserted into the tubular portion 8, as above described, so as to close the baffle and to prevent the further filling of the bottle. Then, by depressing the baffle, the stopper will be forced into the restricted opening 5, so as to effectively close the bottle to prevent the evaporation or accidental discharge of the contents of the bottle. When it is desired to discharge or decant the contents of the bottle, the baffle is drawn outwardly, and the bottle is partially inverted, as seen in Fig. 3, which will permit the contents to flow through the opening 5 into the baffle 7 so as to flow over the lower portion of the apron 9 of the baffle. When the bottle is erected, the same may again be closed by forcing the baffle inwardly.

The baffle will effectively prevent the bottle from being maliciously refilled by unwarranted persons, although the baffle, will permit the contents to be readily discharged or decanted, as above described. The baffle also prevents the contents from being drunk from the bottle direct inasmuch as the mouth cannot be so applied to the device, when the contents are discharged, to accomplish the said result. The present device is also sanitary, and is simple and inexpensive in construction, as well as efficient and convenient in its use.

Having thus fully described the invention, what is claimed as new is:—

1. In combination with a bottle neck, a baffle mounted over the rim thereof and in-

cluding an imperforate apron loosely surrounding the said rim, the baffle having a filling opening, and closure means for the said opening, and constraining the liquid to flow from the bottle neck around the rim thereof and over the apron.

2. In combination with a bottle neck, a baffle mounted over the rim thereof and including an imperforate apron loosely surrounding the said rim, the baffle having a filling opening, means for limiting the outward movement of the baffle, and closure means engaging within the said opening and arranged to close the passage through the bottle neck when the baffle is moved inwardly.

3. In combination with a bottle neck, a baffle mounted over the rim thereof and including an imperforate apron loosely surrounding the said rim, means for limiting the outward movement of the baffle, the baffle having a filling opening and the bottle neck having a restricted opening, and a plug engaged within the said filling opening of the baffle and arranged to enter the restricted opening of the bottle neck when the baffle is moved inwardly.

4. In combination with a bottle neck, a baffle including an annular channel disposed loosely over the rim of the bottle and including a tubular portion disposed loosely within the bottle neck, and an annular imperforate apron loosely surrounding the bottle neck, and a closure for the said tubular portion.

5. In combination with a bottle neck having a restricted opening, an annular channel-shaped baffle disposed over the rim of the neck and including a tubular portion disposed loosely within the neck and an annular imperforate apron surrounding the neck, means for limiting the outward movement of the baffle, and a stopper engaged within the tubular portion of the baffle and adapted to engage the said opening when the baffle is moved inwardly.

6. In combination with a bottle neck, having a restricted opening, a baffle movably carried by the bottle neck and having a filling opening, the said restricted opening being smaller than the filling opening, a stopper having a head to fit snugly within the filling opening, and means carried by the stopper for engaging within the said filling opening to lock the stopper in position, the inner end of the stopper being engageable within the said restricted opening when the baffle is moved inwardly.

7. In combination with a bottle neck having a restricted opening, an annular channel-shaped baffle disposed over the rim of the bottle neck and embodying a tubular portion within the bottle neck and an annular apron surrounding the bottle neck, the apron and bottle neck having means to limit

the outward movement of the baffle, a stopper insertible into the said tubular portion and engageable within the restricted opening of the bottle neck when the baffle is moved inwardly, and interengageable means carried by the stopper and the said tubular portion of the baffle to lock the stopper in position.

8. In combination with a bottle neck, an annular channel-shaped baffle disposed over the rim of the bottle neck and including a tubular portion disposed within the bottle and an annular apron surrounding the rim of the bottle neck, the baffle and bottle neck having means for limiting the outward movement of the baffle, a stopper having an

enlarged head to fit snugly within the said tubular portion, resilient catches carried by the body of the stopper, the tubular portion having means to receive the said catches, 20 when the stopper is inserted, and the stopper being engageable within the said opening of the bottle neck when the baffle is moved inwardly.

In testimony that I claim the foregoing 25 as my own, I have hereto affixed my signature in the presence of two witnesses.

VIRGINIA WESTERVELT SMITH.
